UNITED STATES PATENT OFFICE.

HENRY BERRY, OF HUNTINGTON, ASSIGNOR TO THE DERBY SILVER COMPANY, OF BIRMINGHAM, CONNECTICUT.

DESIGN FOR A CARD-RECEIVER.

SPECIFICATION forming part of Design No. 17,367, dated June 7, 1887.

Application filed March 16, 1887. Serial No. 231,215. Term of patent 3½ years.

To all whom it may concern:

Be it known that I, HENRY BERRY, a citizen of the United States, residing at Huntington, in the county of Fairfield and State of Connecticut, have invented and produced a new and original Design for Card-Receiver; and I do declare the following to be a full, clear, and exact description of the same, reference being had to the accompanying drawing, forming a part thereof.

The figures of the drawing represent the design.

This design has relation to card-receivers; and it consists in the novel form and configuration of the rectangular barred music-rack supported upon a standard, and having laid thereon a leaf of music curled at the ends, as shown and described.

Referring by letter to the annexed drawing, the letter A represents a standard supporting a rectangular barred music-rack, C, and B indicates a leaf curled up at its ends resting on the rack, said leaf having upon it a representation of a bar of music.

I claim—

The design for a card-receiver, consisting of the rectangular barred music-rack supported upon a standard and having laid thereon a leaf of music curled at the ends, as shown and described.

In testimony whereof I affix my signature in presence of two witnesses.

HENRY BERRY.
